CARBONATOR

James O. McMillan, Wichita, Kans., assignor to
Frank J. Ablah, Wichita, Kans.

Application September 9, 1946, Serial No. 695,647

12 Claims. (Cl. 261—84)

1

This invention relates to a carbonator.

The invention is more particularly concerned with a motor-driven carbonator adapted for use within a soda fountain and it consists in the combinations, constructions, and arrangements herein described and claimed.

A primary object of the invention is the provision of a carbonator which comprises relatively few parts but which is capable of carbonizing water in a shorter period of time than is possible with carbonators of the same general character, now in use.

A further and more specific object of the invention is the provision of a carbonating unit which provides three stages of deaeration, agitation, a spray effected simultaneously with the agitation, and a second and adjustable sheet spray and which sprays are effected in a chamber filled with carbon dioxide gas.

A still further object of the invention is the provision of a motor driven carbonator which is fully automatic and having a dependable constant delivery pressure effected by a regenerative turbine pump, the impeller of which functions as a pump on one side and as an agitator on the other side, thus eliminating the use of a speed reducer as well as many other moving parts common in motor driven carbonators.

A still further object of the invention is the provision of a carbonator including a chamber filled with a carbon dioxide gas at a predetermined pressure and into which chamber water is sprayed at selective adjustable pressures whereby the pressure of the water spray is maintained at approximately fifteen pounds above that of the gas pressure for effective saturation of the water by the gas.

A still further object of the invention is the provision of a carbonating unit including an impeller which jointly functions as a pump and as an agitator, together with an adjustable spray means to which water is delivered by the pump.

A still further object of the invention is the provision of a carbonating unit comprising a carbon dioxide chamber, a pumping and agitating means at one end of the chamber and a relatively simple liquid level control at the other end of the chamber.

Other objects and advantages of the invention will become apparent in the course of the following detailed description, taken in connection with the accompanying drawings, wherein—

Fig. 1 is a vertical longitudinal sectional view of the improved carbonator structure, in accordance with a preferred embodiment thereof.

2

Fig. 2 is a left end elevational view of the structure illustrated in Fig. 1.

Fig. 3 is a transverse vertical sectional view in the plane of line 3—3, Fig. 1.

5 Fig. 4 is a side elevational view of the left end portion of the carbonator structure.

Fig. 5 is a transverse vertical sectional view in the plane of line 5—5, Fig. 1.

Fig. 6 is a right hand end elevational view as observed in the plane of line 6—6, Fig. 1.

Fig. 7 is an end elevational view of a pump impeller forming one of the essential elements of the invention.

15 Fig. 8 is a vertical axial section of the structure of Fig. 7.

Fig. 9 is an elevational view of the end of the pump impeller opposite to that of Fig. 7.

Referring now in detail to the drawings, wherein like reference characters designate like parts in the different views, 10 designates a pump housing and 11 designates a liquid control housing which housings are provided with facing concentric circular channels 12 and 13 respectively, in which are received the opposite ends 20 of a stainless steel cylinder 14. Soft rubber gaskets 15 are disposed in the bottoms of the channels 12 and 13 and against which the ends of the cylinder 14 are forced by means of a pair of tie rods 16 having nuts 17 and washers 18 25 on their opposite ends.

30 The end faces of the housings 10 and 11 are preferably of the form of a segment of a sphere (indicated on housing 11 only) whereby to prevent distortion upon drawing up the nuts 17 on the tie rods 16.

35 At this point it is to be particularly noted that the improved carbonating structure includes only three main structures, two housings and the interposed cylinder which are capable of expedient assembly or disassembly by means of only two tie rods 16 and the housings support the essential operating elements for effecting carbonization of the water.

40 The pump housing 10 includes a central cylindrical chamber 19 in which is rotatably supported a shaft 20 by means of ball bearing assemblies 21 and 22 and connected to the inner end of the shaft 20 by means of a key 23 is the hub 24 of a pump impeller 25.

45 The hub 24 of the impeller is disposed between a nut 26 on the inner end of the shaft 20 and one end of a spring 27 whose opposite end seats against a packing 28 in the bottom of a shaft cup-shaped seal 29 whose base rests on a seat member

30 which in turn functions to hold the bearing assembly 21 in position.

The outer end of the shaft 20 is provided with an adjusting nut 31 and a lock nut 32 by means of which the pump impeller may be adjusted in a manner later set forth.

The pump housing 10 is provided with a frusto-conical face 33 in which is formed a semi-elliptical water raceway 34 having a water inlet 35 and a water outlet 36.

The impeller 25 comprises a body portion of generally frusto-conical formation including a face 37 for cooperation with the face 33 on the housing 10.

Cooperating with the semi-elliptical raceway 34 in the housing, is a similar raceway 38 in the face 37 of the impeller and which cooperating raceways jointly define a substantially elliptical raceway co-axially of the shaft 20.

At this point it is to be particularly noted that the cooperating faces 33 and 37 on the housing and impeller respectively as considered in any axial section of the structure, are disposed substantially at an angle of 30° to a vertical plane and it is to be further noted that the major axis of the elliptical raceway extends at a slightly greater angle to the vertical plane.

The impeller 25 is provided with a circumferential series of vanes or blades 39 which are set in the raceway 38 and whose free edges are flush with the face 37 of the impeller.

A highly important feature of the invention is the disposition of such vanes and as will be seen from Figs. 7 and 8, they extend at an angle of 30° in the direction of rotation of the impeller. The vanes also are disposed at a small angle to the axis of the impeller (Fig. 8) and are inclined to the respective radii of the impeller in the direction of rotation thereof (Fig. 7).

The impeller 25 is further provided with agitator vanes 40 on the face thereof opposed to the vanes 39. The vanes 40 are covered by a plate 41 having a water inlet 42 and a water outlet 43 (see Fig. 3).

Water is delivered from the outlet 36 into a priming chamber 44 which is sealed by a plug 45 which, as shown, is tapped to receive a safety valve and manual means for draining off trapped air released from the incoming water.

Water delivered into the chamber 44 by the pump including the impeller 25 passes into a tube 46 and thence into a spray head 47.

The spray head 47 includes a bolt 48 extending vertically through a chamber in the head. A spray regulating plate 49 is supported on the bolt and engages the lower face of the chambered head and a spring 50 is supported on the bolt between the plate 49 and an adjusting nut 51 on the free end of the bolt.

The purpose of the adjustable yieldable support for the spray plate is to hold the water pressure to about 15 pounds greater than that of the carbon dioxide gas which enters the cylinder 14 through the connection 52, and to prevent clogging of spray.

It is to be here noted that water delivered from the agitator vanes 40 passes out through the port 43 in the form of a spray as does also the water from the spray head 47.

The liquid control housing 11 is provided with an outlet 53 for the carbonated water leading to the draft arm of the soda fountain. The housing 11 is further provided with a passage 54 for an electric conduit extending from a drive motor to a mercury switch 55 which is mounted in a bracket

56 pivotally supported on the housing by means of a screw 57 and which is tiltable by a screw 58 connected to a collar 59 on a float stem 60 which is sealed by a packing 61 and washer 62, the washer being engaged by a spring 63 backed by a packing nut 64.

Attached to the float stem 60 is a small stainless steel float 65 which tilts the mercury switch 55 to shut off the motor when the carbonator is fully charged and to switch on the motor when the water level reaches a pre-determined low.

A plate 66 covers and protects the mercury switch 55 which is accessible from the end of housing 11 upon removal of the plate.

The carbonating unit according to this invention is adapted to operate in a soda fountain of relatively low temperature and is provided with suitable bases or feet 67 for the reception of suitable bolts for securing the unit to the floor of the fountain.

The shaft 20 is adapted for operative connection with a motor disposed outside the soda fountain by means of a suitable drive coupling which extends through a tube in the fountain whereby the heat of the motor has no effect on the temperature of the fountain.

In the installation of the improved carbonating unit, it is secured to the floor of the fountain and the motor located externally of the fountain is connected to the shaft 20.

A water line is connected to the pump inlet 35 (see Fig. 2) and carbon dioxide gas from a tank with a regulator valve is connected to the connection 52, the water and the gas both passing through cooling coils in the soda fountain prior to entering the carbonator and at a temperature of about 39 degrees.

With the unit thus installed, the float 65 will be at a low level and accordingly the mercury switch 55 will be tilted to a position to start the motor which through shaft 20 will cause rotation of the impeller 25.

With the unit thus set into operation, water will enter the elliptical raceway 34-38 from the inlet 35 and the vanes 39 in the raceway 38 will impel the water forwardly to the outlet 36 and in so doing the water will be thrown by centrifugal force outwards against the outermost edge of the raceway with a crowding of the water to the left as observed in Fig. 1, and due to the forward inclination of the vanes 39 the centrifugal force on the water will be converted into a force in a tangent direction and due to the elliptical shape of the raceway the water will be crowded and forced into a spiral direction downward and back into the path of the vanes 39 for again being impelled at an accelerated speed and force for augmenting the pressure.

This action on the water is due to the elliptical shape of the raceway and the angular disposition of its transverse major axis to the face 37 of the impeller together with the specific angular disposition of the vanes in the semi-elliptical raceway 38.

Due to the frusto-conical shape of the body portion of the impeller 25, the water is thrown radially outward as well as toward the front of the housing 10 from the inner portion of the raceway to the outer portion thereof which changes the course of the water being impelled and converting its motion into that of a spiral whereby the water is returned for further action by the vanes.

This action on the water frees it of trapped air which is discharged through the valve in plug

45 and the water is then prepared for absorption of the carbon dioxide gas.

As the water enters the priming chamber 44 which functions to prevent the pump from becoming air-locked, it enters the tube 46 and thence the spray head 47 from which it sprays into the cylinder 14 against spring pressure on the spray plate 49 to form a very thin sheet spray for causing the water to absorb the carbon dioxide gas.

The provision of the impeller vanes 40 and their agitating action on the water resulting in a spray from the outlet 43 materially speeds up the impregnation of the gas in the water.

When the carbonated water has reached a predetermined level in the cylinder 14 the switch 55 will be operated by the float 65 to shut off the motor.

The carbonated water is drawn from the outlet 53 and when the level of the water in the cylinder reaches a predetermined low, the switch 55 through action of the float 65 will again set the unit into operation.

From the foregoing it will be appreciated that a carbonating unit has been provided which is relatively simple in construction and which is capable of being mounted in a soda fountain with the expenditure of a minimum of time and effort.

The unit is highly efficient in that the carbonation of the water is effected by a triple action which comprises agitation and a double spray of the water.

By maintaining the water pressure of the spray head 47 at 15 or more pounds above that of the gas a high velocity spray and agitation of liquid in the gas filled cylinder 14 is provided such that the globules of water will be forced to take courses so strenuous and speedy that the impact of same against other globules and the walls of the cylinder will cause rapid absorption of the gas.

In the event of wear between the faces 33 and 37 of the housing 10 and impeller 25 respectively proper adjustment can readily be made by means of the nuts 31 and 32.

While I have disclosed my invention in accordance with a single specific embodiment thereof, such is to be considered as illustrative only, and not restrictive, the scope of the invention being defined in the subjoined claims.

What I claim as new and desire to secure by Letters Patent is:

1. A motor driven carbonator unit comprising an elongated cylinder, a housing supporting one end of the cylinder, an inlet for carbon dioxide gas in said housing, a water inlet in said housing, a rotary pump in said housing for delivering water from said inlet into said cylinder, a second housing supporting the other end of the cylinder, and water level control means supported by the second housing.

2. A motor driven carbonator unit comprising an elongated horizontally disposed cylinder supported by a housing at each end thereof, an inlet connection in one of the housings for admitting carbon dioxide gas into the cylinder, said one housing having a water raceway concentric with said cylinder and a water inlet thereto, a rotary pump supported by a horizontal shaft within said one housing and concentric with said cylinder and operative to force water from said inlet through said raceway, a spray head supported in the upper portion of said cylinder, and a water connection from said raceway to said spray head

and water level control means supported by the other housing.

3. A motor driven carbonator unit according to claim 2 wherein said rotary pump includes a circular wall portion having vanes on one side thereof for forcing water through said raceway, and vanes on the other side of the wall portion operative to agitate water within the cylinder.

4. A motor driven carbonator unit comprising an elongated horizontally disposed cylinder having a supporting housing at each end thereof, the housing at one end of the cylinder having a frusto-conical face converging toward the other end of the cylinder, a circular water raceway in said face concentric with the cylinder and semi-elliptical in cross section, a shaft rotatably supported by said last housing, an impeller drivingly supported by said shaft and having a frusto-conical face engaging the face on the housing, a semi-elliptical raceway in said last face and forming with the first raceway, a raceway of elliptical form in cross section of the housing, an inlet in said last housing for admitting carbon dioxide gas into the cylinder and an inlet for admitting water to said elliptical raceway, said impeller having vanes within the raceway therein for forcing water from said water inlet through the elliptical raceway, a spray head supported within the cylinder adjacent the upper wall thereof, a water connection between the raceway and spray head, and water level control means supported by the other housing.

5. The structure according to claim 4 wherein said faces are disposed at an angle of substantially 30° to a vertical plane and wherein the major axes of the elliptical raceway extend at an angle to the vertical plane slightly greater than 30°.

6. The structure according to claim 4 wherein said vanes have their free edges flush with said faces and wherein the vanes are inclined substantially 45° to the bottom of the raceway with the vanes diverging in the direction of rotation of the impeller.

7. The structure according to claim 4 wherein said impeller is provided with radially disposed vanes projecting axially of said cylinder and away from said face thereof, and a plate covering the last named vanes and having water inlet and outlet openings therein whereby the impeller simultaneously forces water to said spray head, agitates the water and forces it out through said outlet opening in spray formation.

8. The structure according to claim 4 wherein said spray head includes a yieldably and adjustably supported plate for maintaining the spray at a pressure in excess of that of the carbon dioxide gas within the cylinder.

9. In a carbonating structure, an elongated closed cylinder having a housing at one end thereof, a motor driven shaft coaxial with the cylinder and rotatably supported in the housing, the housing having a frusto-conical face adjacent the corresponding end of the cylinder, and converging toward the opposite end of the cylinder, an impeller supported by the shaft for rotation thereby and including a frusto-conical wall portion having one face conforming with and engaging the face on the housing, a circular raceway concentric with the shaft and of elliptical form in axial section of the housing and impeller, the raceway being formed in mating half portions in the face of the housing and the corresponding face of the impeller, circumferentially spaced vanes in the portion of the raceway in

the impeller and terminating flush with said faces, a water inlet in said housing to said raceway, a spray head supported in the upper portion of the cylinder, a water outlet connection from said raceway to said spray head, a disc-like plate supported by said housing and disposed between said wall portion of the impeller and the cylinder, water inlet and outlet openings in the plate, and radially disposed vanes on the opposed face of the wall portion of the impeller for agitating the water and forcing it through said outlet opening in spray form, simultaneously with the pumping of water by the first vanes to the spray head, and a carbon dioxide gas connection in the lower portion of said housing.

10. The structure according to claim 9 wherein in said shaft is axially adjustable for taking up wear between said faces.

11. The structure according to claim 9 wherein in said first vanes are inclined laterally outward-

ly and forwardly in the direction of rotation of the impeller for forcing the water in the raceway outwardly and axially of the impeller with a resulting spiral movement of the water back into the raceway between the impelling vanes.

12. The structure according to claim 9 together with a housing at the other end of the cylinder, said last housing supporting water level control means and having an outlet connection to 10 a soda fountain.
